Primary Examiner — Katherine Glennon*Assistant Examiner* — Yuan Yuan(74) *Attorney, Agent, or Firm* — Bayramoglu Law Offices LLC(57) **CLAIM**

The ornamental design for a hand wraps roller, as shown and described.

DESCRIPTION

FIG. 1 is a top view of a hand wraps roller showing the new design;

FIG. 2 is a perspective view thereof;

FIG. 3 is a front view thereof;

FIG. 4 is a right side view thereof;

FIG. 5 is a rear view thereof;

FIG. 6 is a left side view thereof;

FIG. 7 is a bottom view thereof; and,

FIG. 8 is an exploded view thereof.

The broken lines depict portions of the hand wraps roller in which the design is embodied that form no part of the claimed design.
